UNITED STATES PATENT OFFICE.

ANTON J. HAUG, OF NASHUA, NEW HAMPSHIRE.

PAPER-MAKING MACHINE.

Application filed June 19, 1922. Serial No. 569,236.

To all whom it may concern:

Be it known that I, ANTON J. HAUG, a citizen of the United States, and resident of Nashua, county of Hillsborough, State of New Hampshire, have invented an Improvement in Paper-Making Machines, of which the following description, in connection with the accompanying drawings, is a specification, like characters on the drawings representing like parts.

This invention relates to paper-making machines, and more particularly to apparatus for, and process of, separating from liquid material suspended therein, and thickening the same to a web-forming consistency. The invention contemplates the removal of the thickened stock from the machine, either in web form or in bunches, as desired, as well as the employment of means to further dry out and strengthen the stock-web formed by the operation of the machine—all as hereinafter set forth and illustrated by the accompanying drawings.

In the drawings:

Figure 1 is a sectional, end elevation, looking toward the drive end, of a preferred form of machine embodying the invention, said sectional elevation being taken on line A--A of Fig. 2;

Fig. 2 is a sectional side elevation of the same machine, showing the stock inlet, trough, and screw conveyor partly in section;

Fig. 3 is an end elevation of the machine, showing the stock inlet and the outlet for the thickened stock;

Fig. 4 is a plan view of the stock inlet;

Figs. 5 and 6 are fragmentary details showing the construction of the screen drum of the same machine;

Figs. 7, 8, 9 and 10 show other means, within the scope of the invention, for removing the thickened stock from the screening surface;

Figs. 11 and 12 are diagrammatic sketches, showing means for further drying and strengthening the stock-web formed by the operation of the machine, and leading the same to the exterior thereof; in Fig. 11, an inclined shute being employed for the discharge of the stock-web, while in Fig. 12, means are shown for positively conveying the said web out of the machine;

Figs. 13 and 14 are plan views of Figs. 11 and 12, respectively.

In the drawings, 1 represents a casing closed at both ends, with the exception of an inspection opening 2 (Fig. 3), through which the operation of the machine may be observed. Within said casing, a screen drum 3 is revolubly mounted, said drum being constructed with end members 4 and 5, the former shown as a spider containing hub 6, keyed to shaft 7, and the latter as a rim, with the diameter of its inner circumference smaller than that of the screen drum, whereby to prevent the stock from spattering out of said drum at that end of the machine.

The outer circumferences of end members 4 and 5 are connected by a plurality of rods or bars 8 (Figs. 5 and 6) and said rods are encircled, at regular intervals, by a number of rings 9, the latter being held mutually equidistant by pipe braces 10, which are slipped over rods 8, between the respective rings. The whole frame-work is stiffened and held rigid by nuts 11 on the ends of the aforesaid rods. Over said framework, wire 12 and facing 13 are secured.

Shaft 7, upon which the screen drum is mounted for revolution, rests in bearings 14 and 15, supported by brackets 16 and 17, cast in the respective ends of the casing. 18 indicates a pulley keyed to the said shaft and adapted to rotate the latter by means of power transmitted from any convenient source.

19 represents one of a pair of brackets which are fastened to each end of the rear wall of stock trough 20. Said brackets constitute a support to which arms 21 are pivotally connected, said arms being adapted to hold the journals 22 of couch roll 23 in such position that its surface closely approaches the inner surface of the screen drum.

Arms 21 are connected, at their other extremities, by bar 24, the arms and said connection forming a single, rigid member. In connecting bar 24, a hub 25 is arranged to carry threaded rod 26, which is, at one end, pivotally held in bracket 27, fastened to the wall of the stock trough, and at the other end, is equipped with spring 28 and hand-wheel 29.

Depending extensions of arms 21 form supporting members 31, to which doctor 32 is pivotally fastened at each end of the couch roll, the pivots being denoted at 33.

The said doctor is held, in the manner described, so that its edge is in tangential relation to the couch roll, and thus adapted to divert the stock-web therefrom. The pressure of the doctor edge against the couch roll surface may be adjusted by regulating weight 34, carried by lever 35.

While couch roll 28 constitutes ample means for removing the thickened stock from the screening surface, the functioning of said couch roll is preferably facilitated by the provision of pipe 36, from which a blast of air or other fluid under pressure is directed upon the outer screening surface, and adapted to assist the couching action of the roll. Pipe 36 is inserted in hubs 37 and 38, provided in the respective upper ends of the sides of casing 1.

Stock trough 20 forms part of inlet casting 39, said inlet having its intake at 40 and spreading out in the interior of the screen drum, as shown in Fig. 4, to form stock reservoir 41. This reservoir is longitudinally coextensive with the screen drum, and its outer edge is dammed by weirs 42 and 43, over which the stock must flow in order to reach the surface of the screening drum. By thus backing up the stock and obliging it to flow over dams, a steady, even distribution of said stock upon the screening surface is insured.

Within stock trough 20, a screw-conveying member 44 is shown fastened to the shaft and adapted to revolve therewith, thereby screwing the stock which falls into said trough along the same toward outlet 45, where it is delivered into chute 46 and discharged from the machine. This conveying member is not necessary to the efficiency of the machine, for the trough may be inclined downwardly and the thickened stock caused to travel along the same toward the outlet end of the machine by gravity and the head of the stock behind.

At 47, is shown an outlet for the liquid or white water which has been drained from the stock by the operation of the machine.

In operation, paperstock, or other material suspended in liquid, is fed to the interior of the screen drum thru intake 40, where it spreads out in stock reservoir 41, and finally flows over dams 42 and 43, falling, by gravity, in a continuous, even stream, against the inner surface of the screen drum, along the entire length thereof.

The rapid rotation of the screen drum develops centrifugal force, in a greater or less degree, according to its speed, and causes the stock delivered upon the inner surface of said drum to adhere thereto during the revolution of the drum. The said centrifugal force further acts upon the stock, now adhering to the revolving screening surface, to drive the liquid in

said stock thru the perforations in said surface, leaving the stock thereon in a relatively drier condition.

The stock, by being thus subjected to the operation of centrifugal force, in the machine described, may be thickened to any desired consistency, within certain limits, depending upon the practicability of constructing and driving machines of this type, beyond a certain size. The desired degree of dryness of the stock is herein obtainable by regulating the speed of the screen drum, of given diameter, and the pressure between the inner surface of said drum and the contacting surface of the couch roll. For example, if stock of great dryness is desired, a high speed of the drum in combination with increased pressure between the surface of the couch roll and the said drum will give the desired results.

When, therefore, it is desired to move the couch roll closer to the surface of the screen drum, in order to obtain this increased pressure, hand-wheel 29 is turned, spring 28 compressed, and the supporting arms 21 are caused, thru the pressure applied to their connection 24, to swivel about their pivots 30 and carry the couch roll upwardly for the desired distance.

In Fig. 7, the couch roll shown in Fig. 1 is replaced by bar 48, held rigidly in working proximity to the inner surface of the screen drum. Said bar may be covered with felt, or other soft, flexible material, so that it may be brought closely proximate the screening surface, for the purpose of scraping the stock therefrom, without possibility of injuring the screening wire. In operation, the edge of this felt-covered member is caused to oppose the thickened stock which is being carried on the revolving screening surface, to scrape said stock from said surface, and guide it toward the trough provided below.

Fig. 8 shows a stationary pipe 49, located outside the screen drum and adapted to supply a continuous current of air, or other fluid under pressure, to the screening surface. Said pipe is purposely placed so that it operates upon a portion of the screening surface slightly in advance of the part adjacent the edge of doctor 50, which is held rigidly proximate the inner screening wall. The edge of said doctor is not necessarily brought in such close proximity to the screening surface, as is the edge of bar 48 in Fig. 7, since the lifting of the thickened stock from the screening surface is here accomplished by the air from pipe 49, the doctor in this figure being provided merely to further alter the path of the stock, already lifted from the screening surface, and cause the same to fall into the trough below.

It should be noted, in connection with

the application of the invention in the construction just described, that with this arrangement, as well as with the couch roll, it is possible to remove the stock from 5 the screening surface, without disturbing the web, which has formed by the operation of the machine.

In Fig. 9, the means for removing the stock from the screening surface is further varied. A roll 51 is here shown, with its surface in working proximity to the screening surface. In this arrangement, however, the roll does not receive its power to revolve from contact with the revolving screen drum, but is driven by means of pulley 52, provided on its journal, and cross belt 53, which receives its power from a pulley on the main shaft, and thus drives the roll in the direction opposite to that of 15 the revolution of the screen drum. The surface of this roll is preferably covered with some soft material, such as felt, rubber, etc. In operation, this oppositely-rotating roll scrapes the stock from the screening 20 surface. The stock, thus removed, is guided, in its downward movement, by doctor 54, having its edge in contact with the surface of said roll.

Fig. 10 shows the roll in Fig. 9 replaced by a brush roll 55, which is adapted to be driven, by the means shown, in either direction. Said roll and deflector 56 may be employed, for the purposes of the invention, with substantially the same results 35 as the corresponding roll and deflector in Fig. 9.

In Fig. 11, 57 and 58 are press rolls, supported in any suitable manner, and so positioned that the surface of one of said 40 rolls, here roll 57, operates in working proximity to the surfaces of the couch roll 59 and of the press roll 58. In operation, the couch roll diverts the thickened stock, in web form, from the inner surface of the 45 screen drum to its own surface. The stock web on the surface of the couch roll is further pressed and strengthened by passing between the contacting surfaces of the couch and press roll 57, the latter roll being 50 constructed to pick up the stock, after this pressing action, and carry it on its own surface, whereon it is again pressed at the 55 point of contact of the two press rolls, whence it falls by gravity onto chute 60. This chute is arranged at an angle to the 60 axis of the screen drum, and is inclined downwardly from the drive end toward the outlet end of the machine, providing a course along which the stock-web moves, by gravity, out of the machine.

Fig. 12 shows a similar arrangement, an additional pair of press rolls 61 and 62 being provided to further dry out the stock web, which after passing between the contacting surfaces of said rolls, falls upon

conveyor 63, by which it is carried to any desired point outside the machine.

The illustrations referred to herein show particular applications of the invention, but it should be understood that the main features thereof admit of employment in numerous different combinations. For instance, the screen drum may be either horizontal, as shown, or vertical, and cylindrical, 70 polygonal or conical in form. Furthermore, 75 various means, in addition to those described, may be employed for diverting the thickened stock from the screening surface, either with or without disturbing the stock-web, and for further drying the said web 80 and removing same from the machine—all within the broad scope of the invention.

I claim:

1. In a machine for handling dilute paperpulp or other material suspended in liquid, 85 the combination with a screen drum, of means to rotate said drum rapidly to thicken the stock contained therein by centrifugal force, and a roll adapted to operate in said drum. 90

2. In a machine for handling paperstock, the combination with a screen drum, of means to rotate said drum rapidly to thicken the stock contained therein by centrifugal force, of a couch roll adapted to 95 operate in said drum.

3. In a thickener for dilute paperpulp or other material suspended in liquid, the combination with a screen drum, of means to rotate said drum rapidly to thicken the 100 pulp contained therein by centrifugal force, and a roll adapted to operate in working proximity to the inner surface of said drum.

4. A thickening machine for dilute paperpulp comprising in combination, a screen 105 drum adapted to develop centrifugal force and a revoluble member therein, said drum and member being positioned to revolve around independent axes.

5. In a machine for handling relatively dilute paperstock or other material suspended in liquid, the combination with a screen drum adapted to develop centrifugal force, of revoluble means for removing the stock from the inner surface of said drum, 110 said stock-removing means and said drum being positioned to revolve around independent axes. 115

6. In a machine for handling relatively dilute paperstock or other material suspended in liquid, the combination with a screen drum, of means to rotate said drum rapidly whereby a substantial centrifugal effect is exerted upon the stock contained therein, and means, driven by contact with the inner surface of said drum, to remove the thickened stock from said surface. 120

7. A paperpulp handling machine comprising, in combination, a screen drum, means to rotate said drum rapidly, whereby 125

- 4
- the pulp contained therein is centrifugally held upon the inner surface of said drum to thicken said pulp, of means to remove the pulp from said surface, said pulp-removing means being adapted to revolve by reason of its contact with the surface of the screen drum, around an independent axis.
8. In a thickening machine for paperpulp, the combination with a screen drum, 10 on the surface whereof a pulp-web is adapted to be formed by centrifugal force, of an agency to divert the pulp-web from said surface, said web-diverting agency and said screen drum revolving around independent axes.
9. A machine for thickening relatively dilute paperpulp or other material suspended in liquid, comprising, in combination, a screen drum and means provided 20 therein to remove the thickened stock, in web form, from the screening surface.
10. A papermaking machine comprising, in combination, a screen drum, means to distribute the stock upon the inner surface 25 of said drum, and means to remove the thickened stock, in web form, from the said surface.
11. A papermaking machine, comprising, in combination, a screening member, where- 30 on a pulp-web is adapted to be formed by centrifugal force, and means to remove the said web intact from the said member.
12. A papermaking machine having a screen drum, means to form a pulp-web on 35 the inner surface of said drum, and means to remove said web, in undisintegrated condition, from the said surface.
13. In a thickening machine for relatively dilute paperpulp or other material suspended in liquid, the combination with a screen drum, of means to deliver pulp upon 40 the inner surface of said drum, along the entire length thereof, means to form a pulp-web upon the said surface, and means to remove the said web intact therefrom.
14. A thickening machine for relatively dilute paperpulp or other material suspended in liquid, comprising, in combination, a screen drum, a pulp inlet longitudinally co-extensive with said drum, and one 45 or more members adapted to remove the pulp from the inner surface of said drum.
15. A papermaking machine having, in combination, a screen drum, a stock inlet longitudinally co-extensive with said drum, and a roll adapted to operate within the 55 screen drum.
16. A papermaking machine having, in combination, a screen drum, means to distribute the incoming stock upon the inner surface of the said drum, along a line parallel to the axis thereof, on which surface the stock is adapted to be thickened to a 60 web-forming consistency by centrifugal force.
17. In a papermaking machine, the combination of a screen drum, with a pulp inlet to distribute the stock upon the inner surface of said drum, and means to divert the thickened stock from the said surface, said inlet and stock-diverting means being adapted to operate along parallel lines on the screening surface.
18. A papermaking machine comprising, in combination, a screen drum, a stock inlet 75 longitudinally co-extensive with said drum, and a roll adapted to remove the thickened stock, in web form, from the inner surface of the screen drum.
19. In a papermaking machine, the combination of a screen drum, with means to supply stock to the inner surface of said drum along the entire length thereof, upon which surface a stock-web is adapted to be 80 formed by centrifugal force, and means to divert the said web intact from the screening surface.
20. In a papermaking machine, the combination with a screen drum, of means to rotate said drum rapidly to form a stock-web 90 on the inner surface thereof by centrifugal force, and a roll to remove the stock-web intact from the screening surface.
21. In a papermaking machine, the combination with a screen drum, upon the inner 95 surface of which drum the stock is adapted to be thickened by centrifugal force, and a trough to guide the thickened stock toward the outlet end of the machine.
22. In a papermaking machine, the combination with a horizontal screen drum, of a stock inlet longitudinally co-extensive with the said drum, a stationary stock guideway therein, and means revolvable in 100 said guideway to move the thickened stock 105 toward the outlet of the machine.
23. In a papermaking machine, the combination with a screen drum, of means to rapidly rotate said drum whereby the stock 110 therein is thickened to a web-forming consistency, and stationary means, also within the screen drum, to guide the stock to the outlet of the machine.
24. In a centrifugal papermaking machine, the combination with a screen drum, of a stock deflector therein axially parallel to the said drum and adapted to remove the stock from the inner surface thereof. 115
25. In a centrifugal papermaking machine, the combination with a screen drum, of a member to divert the thickened stock 120 from the inner surface of said drum, said member being adjustable with respect to its proximity to the screening surface.
26. A centrifugal papermaking machine comprising, in combination, a revolvable screen drum, and a stock diverting member therein, said member being driven by contact with the surface of said drum. 125
27. A centrifugal papermaking machine 130

- comprising, in combination, a revoluble screen drum, and a stock deflector therein, said deflector being driven by contact with the surface of said drum, and adjustable 5 with respect to its proximity to said surface.
28. In a papermaking machine, the combination with a screen drum adapted to develop centrifugal force, of a roll provided to operate within the said drum and a member 10 in tangential relation to said roll.
29. A papermaking machine comprising, in combination, a casing, a screen drum revoluble therein, a roll proximate the inner surface of said drum and revoluble by contact therewith, an inlet to distribute stock upon the inner surface of the screen drum, a stock trough to guide the thickened stock toward the outlet end of the machine, and an outlet for the thickened stock.
- 20 30. A papermaking machine comprising, in combination, a screen drum adapted to develop centrifugal force, a stock reservoir therein, and a stock intake communicating with the said reservoir.
- 25 31. The process of handling paperstock which consists in depositing the same upon the inner surface of a screen drum, rotating the same rapidly to form a stock-web, by centrifugal force, on said surface and diverting the said web intact from the screening surface.
32. The process of handling relatively dilute paperstock or other material suspended in liquid which consists in subjecting the stock to a preliminary agitation, preparatory to its deposit on a screening surface, depositing said stock upon said surface, simultaneously along the entire length thereof, forming a web thereon by centrifugal force, and removing the web intact from the said screening surface.
- 35 33. The process of handling relatively dilute paperstock or other material suspended in liquid in a screen drum which consists in distributing the incoming stock upon the inner surface of said drum along a line extending the entire length of said surface, and removing stock in web form from the screening surface, along a line thereon parallel to the line of distribution.
- 40 34. The process of thickening relatively dilute paperstock or other material suspended in liquid in a screen drum which consists in subjecting all the stock entering the said drum to centrifugal thickening action of predetermined duration.
- 45 35. The process of handling paperstock in a screen drum which consists in subjecting all the stock entering the said drum to a centrifugal thickening action of predetermined duration, the duration of said thickening action in any given machine depending entirely upon the speed of revolution of the screen drum.
36. In a machine for handling paperpulp or other material suspended in liquid, the combination with a screen drum, of means to rotate said drum rapidly to thicken the pulp deposited on the inner surface of said drum by centrifugal force, air or other fluid under pressure from the outside to lift the thickened pulp from the screening surface, and a cooperative member inside the screen drum to guide the diverted pulp toward the axis of the said drum.
- 75
37. As an article of manufacture, a paperpulp handling machine having a screen drum consisting of a plurality of rods parallel to the axis of said drum, a series of flat rings provided to encircle said rods, 80 said rods being mutually spaced apart and held in place by pipe braces fitted over the said rods between the respective rings, nuts on the ends of said rods to stiffen the entire framework—the whole being covered with 85 suitable wire-screening.
38. A thickener for paperpulp having a horizontal drum and stationary means to remove the thickened stock from the inner surface of said drum.
- 90
39. A centrifugal thickener for paperpulp having a horizontal drum and stationary means to remove the stock from the inner surface of said drum.
40. In a machine for handling relatively dilute paperpulp or other material suspended in liquid, the combination with a screen drum, of means to distribute pulp upon the inner surface of said drum, and a roll to remove the pulp, in web form, 100 from said surface.
- 45 41. In a papermaking machine, the combination with a screen drum, of a roll to divert the thickened stock from the inner surface of said drum, and a member provided to exert pressure upon said roll to adjust the proximity thereof to the screening surface.
- 105
42. In a papermaking machine, the combination with a screen drum, of a roll to divert the thickened stock from the inner surface of said drum, and a member provided to exert pressure upon said roll, said member being adjustable to vary said pressure.*

ANTON J. HAUG.
